PRESSING MACHINE

Jacob Silverman, Brooklyn, N.Y.

Application March 10, 1958, Serial No. 720,350

14 Claims. (Cl. 223—2)

The present invention relates to a machine for pressing sheets, and particularly pouch-like composite sheets such as are used as flaps and cuffs for the pockets of coats, jackets and the like.

Pocket flaps usually comprise upper and lower sheets of material secured together at three sides to define a pouch and adapted to be secured along their fourth side to the garment with which they are used. In the past these flaps have been pressed by placing them on a die which holds them taut, then pressing the flap while it is on the die through the application thereto of heat and pressure, often accompanied by steam, and thereafter removing the flap from the die. There are certain drawbacks involved in this prior art procedure which have been tolerated because they were thought to be unavoidable. It is difficult and time consuming to slide the pouch-like flap onto the die and to arrange it thereon in proper position to be pressed. Removal of the flap from the die involves the application of appreciable force which often leads to destruction or deterioration of the results of the pressing operation. Unless different dies are provided or the size of the die is adjusted for each different size of flap, even if the size difference is very small, the efficacy of the pressing operation is minimized, since it is important that the flap be pressed in a tautly stretched condition, and the die is relied upon to produce that condition. Also, because the dies themselves are subjected to the heat of the pressing operation, which usually lasts for an appreciable period of time, they tend to become quite hot after a few pressings, and this makes for considerable difficulty on the part of the operator in removing pressed flaps therefrom and placing new flaps thereupon. Moreover, since the die must be present at the pressing station while pressing takes place, no pressing can occur while a flap is being placed upon or removed from the die, and thus the output of a given machine in terms of the number of pressed flaps which can be produced in a given period of time is greatly limited.

The pressing machine of the present invention avoids all of these drawbacks, and does so by means of a structure which is simple, inexpensive, and substantially fool-proof.

In the machine of the present invention the die is utilized to stretch the flap taut and to convey it to the pressing station. However, once the flap has reached the pressing station the die is withdrawn therefrom, and thereafter the flap is pressed. Thus the die is not subjected to the heat involved in the pressing operation and it is, moreover, available during the time that the pressing operation takes place for the application thereto of a new flap. The insertion of each new flap into the pressing station ejects the previously pressed flap therefrom. Thus the removal of the flap from the die and the ejection of the flap from the pressing station are entirely automatic, and all the operator need do is apply new flaps to the die as they are needed, and this, it will be noted, in an extremely efficient manner from a production time point of view.

To accomplish these results, and to facilitate the plac-

2

ing of the flap thereon, the die is of variable size, and will adapt itself within limits to flaps of different sizes without requiring adjustment. A handle is provided to control the size of the die. The die is converted to its smaller size, the flap is placed thereon, this being an easy operation because the die is then smaller than the flap, and the die is then manually converted to its larger size, in which it holds the flap taut. The die, with the flap thereon, is then moved to the pressing station, where the flap is frictionally gripped. Reconversion of the die to its smaller size results in the die engaging the flap with much less force than does the pressing station. Accordingly, the die may be withdrawn, the flap will remain in the pressing station, and the pressing operation can then take place, the die then being free for the application thereto of a new flap while the pressing of the preceding flap occurs.

While the conversion of the die from its large to its small size when in the pressing station may be manually accomplished, it is preferred that this be accomplished automatically, and means to that end are here specifically disclosed.

It is usually desired that a steam pressing operation be carried out. To this end the movement of the die, with the flap attached, toward the pressing station automatically causes a jet of steam to be applied to the flap, thus conditioning the latter for the subsequent pressing operation.

As here specifically disclosed the pressing operation is manually initiated, as by stepping upon a foot treadle or the like, and a timer is provided so that, when once initiated, the pressing operation will continue for a desired period of time and will then terminate.

To the accomplishment of the above, and to such other objects as may hereinafter appear, the present invention relates to the construction of a pressing machine as defined in the appended claims and as described in this specification, taken together with the accompanying drawings, in which:

40 Fig. 1 is a three-quarter perspective view of the machine of the present invention with the die shown in standby position;

Fig. 2 is a side elevational view of the machine of Fig. 1, taken from the direction of the line 2—2 of Fig. 1;

45 Fig. 3 is a top plan view of the machine of Fig. 2 but with the die in the pressing station;

Fig. 4 is a cross sectional view taken along the line 4—4 of Fig. 3;

Fig. 5 is a cross sectional view similar to Fig. 4 but showing the die withdrawn from the pressing station and on its way to its normal standby position, the flap previously carried by the die being shown in the pressing station;

Fig. 6 is a fragmentary top plan view of a portion of the die showing the manner in which the die is converted from large to small size; and

Fig. 7 is a three-quarter perspective view on a reduced scale of the die with a flap applied thereto.

The machine comprises a support generally designated 60 2 and carrying a table 4 on which a pressing station 6 is provided, that pressing station being defined between a fixed plate 8 which overlies the table 4 and a pressure plate 10 thereunder which is adapted to move upwardly through an aperture 12 in the table 4. Any suitable heating means, preferably electrical, is active on the pressure plate to maintain it at an elevated temperature. The die, generally designated 14, is mounted on a carriage 16 slidable along arm 18, which is pivotally mounted at 20 adjacent that end of the table 4 opposite the pressing station 6, the die 14 being movable from its standby or loading position shown in Figs. 1 and 2, in which it is above the table 4 and beyond the pressing station 6, to

an intermediate position (see Fig. 5) on the table 4 and beyond the pressing station 6, and then to a final delivery position (see Figs. 3 and 4) in which it enters the pressing station 6.

In order to bias the die 14 to its standby position a pair of stretched springs 22 are connected between the carriage 16 and an arm 24 secured to and extending rearwardly from the arm 18, these springs therefore urging the carriage 16 to a rearward position along the arm 18 as viewed in Fig. 1. Extending downwardly from the rearwardly projecting end of the arm 24 is a hook 26, and a tension spring 28 is connected between that hook 26 and a portion of the support 2, the spring 28 being active to urge the arm 18 to pivot upwardly, as best shown in Fig. 2. The carriage 16 is provided with a handle 30 to facilitate its manual manipulation.

The carriage 16 has a mounting part 32 to which a plate 33 is fixedly secured at one side thereof, that plate having an elongated slot 34 extending therethrough. A plate 35, also provided with an elongated slot 34, is pivotally mounted on the underside of the plate 32 at 44. The die 14, in the form here specifically disclosed, comprises a pair of side plates 36 and 38. The plate 36 is secured to the plate 33, and is adjustably positionable relative thereto, by means of a clamping screw 40 which passes through the slot 34 in the plate 33 and which, when screwed down, clamps the plate 36 to the plate 33. The position of the plate 36 may be adjusted to correspond to flaps of different sizes by virtue of the position of the clamping screw 40 along the slot 34 through which it passes. The plate 38 is secured to the plate 35 by the clamping screw 46 in a manner comparable to that of plate 36. An ear 48 extends rearwardly from plate 35 and is connected by means of tension spring 50 to an ear 52 forming a part of the plate 33. The spring 50 biases the plate 38 to pivot in a counter-clockwise direction as viewed in Figs. 1, 6 and 7. The plate 32 has a laterally projecting portion 54. Cam 56 is positioned therebelow in engagement with the side edge of the plate 35, is pivotally mounted about pin 58, and has an outwardly projecting portion 60 to which handle 62 is connected by means of pin 64, the handle 62 and cam 56 pivoting as a unit about the pin 58. The shape of the cam 56 is such that when it is moved to its forward position shown in solid lines in Fig. 6 it will permit the plate 38 to pivot outwardly to a predetermined degree, and when the cam 56 and handle 62 are moved rearwardly, to their positions shown in Figs. 1 and 3 and in the broken lines in Fig. 6, the plate 38 will be forced inwardly thereby, pivoting in a clockwise direction against the action of the spring 50. The cam 56 is further so designed as to function in an over-center manner so that, when in either of its limiting positions described above, the pressure of the plate 38 thereon, derived from the spring 50, will tend to cause the cam 56 to remain in that position. It will therefore be seen that when the handle 62 is in its forward position the plate 38 will move laterally away from the plate 36, thus causing the die 14 to have a predetermined width, and when the handle 46 is moved to its rear position the plate 38 will be moved laterally toward the plate 36, thus causing the overall width of the die 14 to decrease, the die therefore assuming a smaller size.

The aperture 12 in the table 4 is of appreciable width, and is located partially under the plate 8 and partially therebeyond toward the rear of the table 4. The die 14 is so positioned on the arm 18 when in its normal withdrawn position as urged by the springs 22, that when the arm 18 is pivoted downwardly at least the leading portion of the plate 36 and 38 assume a position thereabove, and consequently above the pressure plate 10 which substantially fills the opening 12 but is freely movable vertically therethrough. Springs 66 carried by cross bars 68 beneath the table 4 urge the pressure plate 10 to a raised position, best shown in Fig. 4, toward but

spaced from the plate 8. The pressing station 6 is defined between the plate 8 and that portion of the pressure plate 10 thereunder, and it will be noted particularly from Figs. 4 and 5 that this pressing station is provided with an open end 70 facing the rear portion of the table 4 and an opposite open end 72 facing the front end of the table 4 and communicating with a table extension 74 from which a shelf 76 may be suspended.

The pressure plate 10 is provided, on that portion thereof over which the die 14 is positioned, with a hole 78 to which a stream duct 80 is connected, that duct in turn communicating with a suitable source of steam via normally closed valve 82 adapted to be actuated by solenoid 84. The solenoid is in turn electrically connected to microswitch 86 the actuating button 88 of which extends up through a hole 90 in the table 4 to one side of the die 14. A bracket 92 carries a pivotally mounted arm 94 the end of which is positioned over the button 88 and which is provided with an extension 96. The die carriage 16 has an arm 98 extending therefrom and carrying a roller 100 so positioned that when the die 14 is moved downwardly from its position shown in Figs. 1 and 3 to its position shown in Fig. 5 the roller 100 will engage the extension 96, and force the lever 94 down, thereby depressing button 88, energizing solenoid 84, opening valve 82, and causing a jet of steam to issue upwardly through the hole 78. When the die 14 reaches its lowermost position, the roller 100 will have passed off from the extension 96, the arm 94 will no longer depress the button 88, the valve 82 will close, and the jet of steam will stop. Thus it will be seen that each time that the die 14 is depressed a jet of steam of limited duration will emerge from the hole 78.

Means are provided for urging the pressure plate 10 upwardly with considerable force in order to produce a pressing operation. As here disclosed, that means comprises a pressure pin 102 adapted to engage the underside of the pressure plate 10 and carried by arm 104 pivotally mounted at 106 beneath the table 4 and provided with spring 108 active between it and the table 4 to tend to urge the arm 104 to pivot in a clockwise direction as viewed in Figs. 4 and 5, thereby to withdraw the pin 102 from the pressure plate 10. A second arm 110 is pivotally mounted beneath the table 4 at 112, is operatively connected to the arm 104 at 114, and is provided with a spring 116 tending to urge it to pivot in a counter-clockwise direction. A portion of the arm 110 extends out beyond the front of the support 2, and is there connected to a chain 118 the other end of which is secured to a foot treadle or hand lever 120 (see Fig. 2). Depending from the arm 110 is an arm 122 carrying a roller 124 at its lower end and urged by means of spring 126 toward the front of the support 2, that front being provided with a cutout 128 into which the roller 124 may be received when the foot treadle 120 has been depressed. A solenoid 130 is located opposite the cutout 128 and is provided with an armature 132 to which pin 133 is connected by means of brackets 135, a space being provided between pin 133 and armature 132. A plate 134 is received in that space, the plate 134 being secured to the arm 122 at 137. A switch 136 has an actuating button 138 positioned beneath the arm 110 and adapted to be depressed whenever the arm 110 is moved to its position shown in Fig. 5, that switch being electrically connected to adjustable timer 140 which in turn controls the action of the solenoid 130.

When the machine is to be used the die 14 is in its raised standby position shown in Figs. 1 and 2. The handle 62 is rearwardly positioned, thus causing the width of the die 14 to contract. The sheet to be pressed, generally designated 141, and here specifically disclosed in pouch form and comprising an upper sheet 142 and a lower sheet 144 connected together along one long side and two short sides, is then slipped over the protruding portion of the die 14. This is very easy to accomplish

because with the width of the die contracted it is smaller than the interior of the sheet 141. After the sheet 141 is in proper position the handle 62 is moved forwardly, the die plate 38 moves away from the die plate 36, the width of the die increases, and the sheet 141 is thus held tautly on the die, the plates 36 and 38 having been previously positioned on the mounting part 32 in order that this result is obtained. It may be noted at this point that because of the resilient mounting of the plate 38 the die 14 will accommodate itself to variations in the size of individual sheets 141, within limits, without requiring any readjustment on the carriage 16.

Next the handle 30 is grasped and depressed. This brings the sheet 141 directly over the steam hole 78 in the pressure plate 10 and engagement between the roller 100 and the extension 96 on the arm 94 causes a jet of steam to be applied to the sheet 141.

When the die 14 has been depressed sufficiently so that the sheet 141 is resting on the pressure plate 10, the handle 30 is then pulled forwardly, causing the carriage 16 to slide along the arm 18. The leading portion of the die 14, on which is carried the sheet 141, thus enters the pressing station 6 through the open end 70 thereof. Just before the die 14 reaches its final position in this direction, a pin 146 projecting up from the table 4 engages the outwardly protruding portion 60 of the cam 56 and swings the cam 56, and with it the handle 62, to its rear position, thus causing the plate 38 to move toward the plate 36 (see Fig. 3). As a result the sheet 141 is no longer taut on the die 14. However, the springs 66 urge the pressure plate 10 upwardly with sufficient force so that the sheet 141 is frictionally gripped between the pressure plate 10 and the plate 8. The sheet 141 will therefore retain its shape even though the die 14 has contracted in size.

Next the handle 30 is pulled to the rear, withdrawing the die 14 from the pressing station 6. Because the sheet 141 is no longer tautly stretched thereon, and because the sheet 141 is frictionally gripped between the plate 8 and 10 by reason of the action of the springs 66, the die 14 is retracted from the sheet 141, and that sheet 141 remains in the pressing station 6. The springs 22 and 28 cause an automatic return of the die 14 to its standby position, and the die 14 is in its condition of contracted size, ready to have another sheet 141 applied thereto.

The operator then depresses the foot treadle or hand lever 120 until the roller 124 enters the cutout 128, being urged there by spring 126. When this happens the pressure pin 102 will urge the pressure plate 10 upwardly with considerable force, and the sheet 141 will be pressed. When the arm 110 which actuates the pressure pin 102 has been moved down to its position in Fig. 5 it will automatically engage button 138 of switch 136, closing the latter, and this will in turn close a circuit to the solenoid 130 through the timer 140 which has been previously set for the desired duration of the pressing operation. The circuit through the timer 140 is normally open, the solenoid 130 therefore normally being de-energized. Thus all that is necessary is for the operator to initiate the pressing operation and then release pressure from the treadle or lever 120. The spring 126 will ensure that the pressing operation will continue for the desired period of time. When that time has elapsed the circuit through the timer 140 will close, the solenoid 130 will be energized, its armature 132 will be retracted, the roller 124 will be pulled out from the cutout 128 against the action of the spring 126, and the action of the springs 108 and 116, which have been tensioned during the pressing operation, will cause the arms 104 and 110 to resume their positions shown in Fig. 4, thus withdrawing the pressure pin 102 from the pressure plate 10 and terminating the pressing operation.

It will be appreciated that once the pressing operation has been initiated the operator can thereafter turn his undivided attention to the application of a new sheet 141

onto the die 14, followed by manipulation of the handle 62 to expand the die 14 and hold the new sheet 141 taut.

As soon as the pressing operation has terminated the sequence of operations above described is repeated. As 5 the new sheet 141, carried by the die 14, is inserted into the pressing station 6 it will engage the previously pressed sheet 141 and force it out of the pressing station through the opening 72 thereof and onto the table part 74, where it is available for inspection. If it appears to be in 10 proper condition nothing further need be done, and upon the next succeeding operation the sheet 141 next ejected from the pressing station 6 will force the first pressed sheet 141 beyond the table portion 74 and onto the shelf 76, where completed and properly pressed sheets will 15 stack up in condition for removal. If inspection of the sheet 141 on the table portion 74 indicates improper pressing, the sheet 141 may be manually taken therefrom and re-pressed.

It will be seen from the above that the machine of the present invention is not only sturdy and simple, but also 20 automatic and substantially foolproof. It produces better pressing than machines previously used for this purpose because the flaps or sheets are pressed with the dies removed therefrom, and in addition permits more rapid 25 production, because the die is available for the application thereto of a new sheet while the pressing operation on the preceding sheet is taking place, and more convenient production, because the die is not subjected to heat during the pressing operation and because its size 30 may be varied to facilitate the application of sheets thereto.

While but a single embodiment of the present invention is here disclosed, it will be apparent that many variations may be made therein, all within the scope of the 35 instant invention as defined in the following claims.

I claim:

1. A pressing device for a sheet comprising a support, 40 a pair of spaced overlying plates thereon defining therebetween a pressing station, a member articulately mounted on said support having a portion adapted to carry said sheet, said member being movable between a first position beyond said pressing station and a second position in which said portion is received between said plates at said pressing station, said member portion being variable in size between a large size effective to hold said sheet taut and a smaller size, means carried by said member and operatively connected to said portion to controllably vary the size thereof, and means operatively connected to said member portion, sensitive to the position of said member relative to said support, and effective to cause said member portion to assume its smaller size when said member is in its second position.

2. The pressing device of claim 1, in which said pressing station is open at opposite ends, said member entering said pressing station through one end thereof, the other end thereof serving as an ejection opening for a 55 pressed sheet.

3. The pressing device of claim 1, the space between said plates being so related to the thickness of said member portion as to adapt said plates to frictionally engage the sheet carried by said member portion.

4. The pressing device of claim 3, in which said pressing station is open at opposite ends, said member entering said pressing station through one end thereof, the 60 other end thereof serving as an ejection opening for a pressed sheet.

5. In the pressing device of claim 1, means for admitting steam adjacent said pressing station, control means for stopping and starting the admission of steam thereto, 70 and an interlock between said member and said control means effective to start and then stop said admission of steam as said member moves to its second position.

6. The pressing device of claim 5, in which said control means comprises a valve, a solenoid operatively connected thereto, and a switch operatively connected to 75

said solenoid and controlling the energization thereof, and in which said interlock comprises an element carried by said member and operatively engageable with said switch.

7. The pressing device of claim 1, in which said pressing station has an open end, said member being mounted on said support beyond said open end so as, in its first position, to be above said plates, said member being movable downwardly from its first position to an intermediate position opposite said open end and then being movable substantially horizontally to its second position.

8. In the pressing device of claim 7, means operatively connected to said member and biasing it to its position above said plates, and means operatively connected to said member and biasing it away from said open end of said pressing station.

9. A pressing device for a sheet comprising a support, a carrier member articulately mounted thereon over which said sheet is adapted to be placed, pressing means on said support having a first open end facing said member and a second open end opposite said first open end and communicating therewith via a passage through which said sheets can pass, said carrier member being movable from a first position remote from said pressing means to a second position passing through said first open end and into said pressing means, said pressing means being effective to frictionally engage the sheet carried by said carrier member, whereby when said carrier member is withdrawn from said pressing means the sheet carried thereby will remain within said pressing means, subsequent introduction of sheets into said pressing means causing the ejection of previously introduced sheets via said passage and said second open end.

10. The pressing device of claim 9, in which the size of said carrier member is variable between a larger size effective to hold said sheet taut thereon and a smaller size.

11. The pressing device of claim 9, in which the size of said carrier member is variable between a larger size effective to hold said sheet taut thereon and a smaller size, and means for causing said carrier member to assume said smaller size when it is in its second position.

12. A pressing device for a sheet comprising a support, a pair of spaced overlying plates thereon defining there-

between a pressing station, a member articulately mounted on said support having a portion adapted to carry said sheet, said member being movable between a first position beyond said pressing station and a second position in which said portion is received between said plates at said pressing station, said member portion being variable in size between a large size effective to hold said sheet taut and a smaller size, means for admitting steam adjacent said pressing station, control means for

10 stopping and starting the admission of steam thereto, and an interlock between said member and said control means effective to start and then stop said admission of steam as said member moves to its second position.

13. A pressing device for a sheet comprising a support, a pair of spaced overlying plates thereon defining therebetween a pressing station, a member articulately mounted on said support having a portion adapted to carry said sheet, said member being movable between a first position beyond said pressing station and a second position in which said portion is received between said plates at said pressing station, said member portion being variable in size between a large size effective to hold said sheet taut and a smaller size, means carried by said member and operatively connected to said portion to controllably vary the size thereof, said pressing station having an open end, said member being mounted on said support beyond said open end so as, in its first position, to be above said plates, said member being movable downwardly from its first position to an intermediate position opposite said open end and then being movable substantially horizontally to its second position.

14. In the pressing device of claim 13, means operatively connected to said member and biasing it to its position above said plates, and means operatively connected to said member and biasing it away from said open end of said pressing station.
